UNITED STATES PATENT OFFICE.

EDWARD J. BROOKS, OF EAST ORANGE, NEW JERSEY.

STRAP-TIGHTENING TOOL.

1,313,669.

Specification of Letters Patent.

Patented Aug. 19, 1919.

Application filed October 23, 1918. Serial No. 259,388.

To all whom it may concern:

Be it known that I, EDWARD J. BROOKS, a citizen of the United States, and a resident of East Orange, in the county of Essex and State of New Jersey, have invented certain new and useful Improvements in Strap-Tightening Tools, of which the following is a specification.

The present invention relates generally to a strap tightening device such as is used for tightening the ends of straps that are passed around containers such as wooden boxes, bales, etc., and has for its main object a construction in which the strap tightening member is automatically released from engagement with the strap upon the completion of its feeding stroke so that it may have a return stroke out of engagement with the strap to be tightened.

20 The invention consists in a shifting fulcrum connection between the tightening member and the carrier on which it is mounted so arranged that engagement of the member and strap will be caused during the feeding stroke of said member and disengagement of the strap and tightening member will take place so that the tightening member may have a return stroke out of engagement with the strap.

30 In the accompanying drawings, the invention is disclosed in a concrete and preferred form in which—

Figure 1 is a vertical sectional view of a strap tightening device embodying the invention, the tightening member being shown at the end of its return stroke.

Fig. 2 is a view, partly in elevation and partly in section, with the tightening member shown at the end of its feed stroke.

40 Fig. 3 is a top plan view of the parts in the position shown in Fig. 2, a portion of the handles being broken away.

1 indicates a support of any suitable construction and here taking the form of a base plate having inlaid face portion 2 whose upper surface is roughened so as to properly coöperate with the members presently to be described. 3 is a carrier, in this instance constituting a side wall rising from the base plate, said carrier being connected at one side to said base plate as shown in Figs. 1 and 3 and having its other side wall 3^a provided with an opening 4 to admit of insertion edgewise of the strap ends 5. It will 55 also be understood that the ends 6 and 7 of the device are open so that the strap ends

may pass therethrough. 8 indicates a tightening member. Between this member and the carrier 3 is a shifting fulcrum which in this instance takes the following form. 9 60 is a pin extending from the side wall 3 to the side wall 3^a and passing through a cam slot 10 formed in said tightening member. This cam slot is provided with an upper portion 11 and a lower portion 12 that merge 65 into each other as shown, there being nevertheless an intervening ridge 13 as indicated. The lower end of the tightening member 8 is provided with a face portion 14. The two part cam slot 10 is so related or positioned 70 with respect to the movement of tightening member 8 that during the major portion of the feed stroke of said member pin 9 will occupy the upper portion 11 of the cam slot. As the member 8 is moved to the right in 75 Fig. 1, its face 14 will engage the strap ends 5 upon the support 1 and will cause the strap to be tightened in a manner well understood. After the member 8 has moved past a vertical line drawn substantially 80 through the center of pin 9 it will be approaching the end of its feeding stroke and will shift so that the pin 9 will occupy the lower part 12 of cam slot 10, thereby disengaging face 14 from the strap ends 5, the 85 parts then occupying substantially the position shown in Fig. 2. Said member 8 may now have imparted to it a return stroke to the left from the position shown in Fig. 2 and during that time pin 9 will occupy the 90 portion 12 of the cam slot until said member 8 again passes the vertical center line when pin 9 will again occupy upper portion 11 of the cam slot as shown in Fig. 1.

Suitable means are provided for holding 95 the strap ends so as to prevent retrograde movement thereof during the return stroke of member 8. In this instance, a detent 15 is pivotally supported at 16 on the carrier 3, its lower end 17 being normally urged into 100 engagement with the strap ends by reason of spring 18 which has a bearing 19 on handle portion 20. It will be seen that while detent 15 will prevent retrograde movement of strap ends 5 it will permit tightening of 105 the strap ends under the influence of member 8 during its feeding stroke.

Suitable means for releasing said detent are provided in this instance taking the form of a trigger 21 pivotally mounted at 110 22 on the handle 20 and bearing against pin 23 on detent 15. It will be seen that

by moving trigger 21 from the position shown in Fig. 2 into a higher position, said trigger will engage pin 23 and lift detent 15 so that its lower end 17 no longer engages the strap ends. 24 indicates a stop limiting the movement of trigger 21 and against which it is normally held by gravity. 25 indicates a stop to limit the forward feeding movement of member 8 and 26 indicates a stop portion on carrier 3 which limits the movement of member 8 at the end of its return stroke. In order to facilitate manipulation of the device a handle 27 is provided, said handle being attached to side 15 wall 3^a and which the operator may grasp while manipulating member 8.

I claim—

1. A strap tightening tool comprising: a support for the ends of a strap to be tightened, a carrier, an oscillatory tightening member, and a shifting fulcrum connection between the carrier and member comprising a pin and a slot that automatically shift with respect to each other at the end of a stroke of the tightening member in either direction, the tightening member engaging the strap during its feeding stroke and disengaging the strap during its return stroke.
2. A strap tightening tool comprising: a support for the ends of a strap to be tightened, a carrier, an oscillatory tightening member, and a shifting fulcrum connection between the carrier and member comprising a pin and a slot that automatically shift with respect to each other at the end of a stroke of the tightening member in either direction, the tightening member engaging the strap during its feeding stroke and disengaging the strap during its return stroke, and means for preventing retrograde movement of the strap ends during the return stroke of the tightening member.
3. A strap tightening tool comprising: a support for the ends of a strap to be tightened, a carrier, a tightening member, a shifting fulcrum connection between the carrier and member consisting of a pin and a two part cam slot so related to the movement of the member that during the major portion of the feeding stroke thereof, said pin will occupy the upper part of said cam slot thereby causing said member to engage strap on support, said pin at the end of the feeding stroke of said member automatically shifting to the lower part of the slot thereby causing said member to dis-

engage the strap and admitting of a return stroke thereof out of contact with said strap, the pin again returning automatically to the upper part of slot at the end of the return stroke of said member.

4. A strap tightening tool comprising: a support for the ends of a strap to be tightened, a carrier, a tightening member, a shifting fulcrum connection between the carrier and member consisting of a pin and a two part cam slot so related to the movement of the member that during the major portion of the feeding stroke thereof, said pin will occupy the upper part of said cam slot thereby causing said member to engage strap on support, said pin at the end of the feeding stroke of said member automatically shifting to the lower part of the slot thereby causing said member to disengage the strap and admitting of a return stroke thereof out of contact with said strap, the pin again returning automatically to the upper part of slot at the end of the return stroke of said member, and means for preventing retrograde movement of the strap ends during the return stroke of the tightening member.

5. A strap tightening tool comprising: a support for the ends of a strap to be tightened, a carrier, a tightening member, a shifting fulcrum connection between the carrier and member consisting of a pin and a two part cam slot so related to the movement of the member that during the major portion of the feeding stroke thereof, said pin will occupy the upper part of said cam slot thereby causing said member to engage strap on support, said pin at the end of the feeding stroke of said member automatically shifting to the lower part of the slot thereby causing said member to disengage the strap and admitting of a return stroke thereof out of contact with said strap, the pin again returning automatically to the upper part of slot at the end of the return stroke of said member, and a spring actuated detent admitting of tightening of the strap ends during the feeding stroke of the tightening member and preventing retrograde movement of the strap ends during the return stroke of the tightening member.

Signed at New York, in the county of New York and State of New York, this 17th day of October, 1918.

EDWARD J. BROOKS.
